UNITED STATES PATENT OFFICE.

GEORGE A. MEAD, OF MANSFIELD, OHIO, ASSIGNOR TO THE OHIO BRASS COMPANY, OF MANSFIELD, OHIO, A CORPORATION OF NEW JERSEY.

ELECTRICALLY-OPERATED TRACK SWITCH.

Application filed January 3, 1924. Serial No. 684,250.

To all whom it may concern:

Be it known that I, GEORGE A. MEAD, a citizen of the United States of America, residing at Mansfield, in the county of Richland and State of Ohio, have invented certain new and useful Improvements in an Electrically-Operated Track Switch, of which the following is a specification.

My invention relates to track switches and particularly to electrically and automatically operated track switches under control of the car operator as he approaches the switch.

The object of my invention is to provide a system which can be operated by the car operator by applying the well known principle of "power on" and "power off" the motors and constitutes an improvement over my disclosure in a co-pending application, 20 Serial #679,099, filed Dec. 7, 1923.

My invention resides in the new and novel construction, combination and arrangement of the various electrically operated switches, circuits, etc. hereinafter more fully described and set forth in the drawings accompanying this specification.

In the drawings:

Fig. 1 is a schematic view showing the various circuits usually found in an electrically operated car and which circuits I make use of in the operation of my invention.

Fig. 2 is a schematic drawing showing the arrangement of the various elements making up my invention under normal conditions and with the switch tongue set to the "curve" position.

Fig. 3 is a schematic drawing showing the arrangement of the various elements comprising my invention immediately after the invention has been put into operation by the car operator with "power off" the motors and the track switch shown as thrown to the "straight ahead" position.

Fig. 4 shows a schematic arrangement of the various elements comprising my invention after the system has been set in operation with "power off" the motors and after a predetermined time.

Fig. 5 is a schematic drawing of my invention showing the relation of the various parts after the system has been set in operation with "power on" the motors and the track switch tongue shown as set for the "curve" position.

Fig. 6 is a schematic view showing the

relation of the various elements comprising my invention in a modified form from that shown in the previous arrangements.

Referring to Fig. 1, it is invariably found that electrically operated cars are provided with a current collector W and a trolley pole T connecting the current collector to the car. The car is usually provided with motors M and a controller C for applying "power on" or "power off" the motors at the will of the car operator. The cars are also provided with auxiliary circuits for supplying current to the heaters H, lights L and the air compressor F. The auxiliary circuits are not under the control of the controller C and, therefore, their current is not only variable, depending on which apparatus is in operation, but the current may be considerable as compared with the current flowing through the motors M and, therefore, I take this fact into account in designing certain elements as herein later described. All apparatus derives its current from the trolley wire through the collector W and through a common ground G or separate grounds, as may be desired.

It will be noted that when the operator turns his controller C to the "power on" position that a heavy flow of current will pass through the motors M, but when he turns his controller to the "power off" position no current will flow through the motors M, but current may flow through the apparatus H, L and F. The "power on" and "power off" operation of the controller I make use of for the operation of my invention and I have so arranged my system that with "power on" the motors the switch tongue is automatically set to the "curve" position and when the controller is set to the "power off" position the switch tongue is automatically set to the "straight ahead" position.

Referring to Fig. 2 I employ a contact pan P provided with two contact members 1 and 2 which are placed adjacent the trolley conductor 3 and which are normally insulated from each other and so arranged that when the current collector W engages the pan P the collector will be out of engagement with the conductor 3. However, when the collector engages the pan P the elements 1 and 2 will be electrically connected. It will also be noted that when the collector W engages the pan P that there is also a path for the current to flow from

the contact pan to the ground through the trolley and apparatus H, L and F if in operation, and also through the motors M if the controller is set to "power on". I also employ a track switch A which comprises two solenoids 4 and 5 and having one terminal connected to the ground G through the common conductor 6. The solenoids are provided with a plunger 7 to which a connecting rod 8 is secured which in turn is connected to a track switch tongue 9. When the solenoid 4 is energized the plunger 7 is drawn inwardly as shown in Fig. 3 and the tongue 9 is set for the "straight ahead" position and when the solenoid 5 is energized the plunger 7 is drawn outwardly and the switch tongue 9 is set for the "curve" position as shown in Fig. 2.

I also employ an electrically operated switch B which is provided with two coils 10 and 11 and an armature 12 adapted to engage the contacts 13 and 14, but which is normally in engagement with the contact 13. The contact 14 is electrically connected 25 to the remaining terminal of the solenoid 5 by the conductor 15, while the contact 13 is connected to the remaining terminal of the solenoid 4 by the conductors 16 and 17, switch arm 18 and contact 19. It will be 30 evident that when the arm 12 is deenergized and engages the contact 13 with the switch arm 18 closed, that the solenoid 4 will be energized and the switch tongue thrown to the "straight ahead" position, and if the 35 arm 12 engages the contact 14 the solenoid 5 will be energized and the switch tongue 9 moved to the "curve" position.

I also employ an electrically operated switch C provided with operating coils 20 and 21 and an arm 22, also contacts 23, 40 24 and 25. The switch arm 22 is normally in engagement with the contact 25 and out of engagement with the contacts 23 and 24. The relation of the contacts to the 45 switch arm are such that the arm 22 will engage the contacts 23 and 24 before the circuit is broken at the contact 25, at least the arm should engage the contact 24 before the circuit is broken at 25 for the reasons 50 later given.

One terminal of the coil 10 is connected to the contact member 1 by the conductor 26 and the other terminal is connected to the contact 25 by the conductor 27 and the 55 switch arm 22 is normally connected to the trolley conductor 3 by the conductor 28. It will be evident that when the system is in normal condition, as shown in Fig. 2 that the contact member 1 is electrically connected to the trolley conductor and the coil 10 in series with such connection so that any current passing from the contact member 1 to the contact member 2 or to the ground the instant the collector engages the 60 pan P, such current will pass through the 65

coil 10. The coil 10 is wound preferably with a few turns of large sized wire and its turns are so proportioned that when current is flowing through the motors M, the ampere turns will be sufficient to raise the arm 12, but if the current flowing through the coil 10 is that due to the auxiliary apparatus H, L and F, the ampere turns will not be sufficient to raise the arm 12.

When the contact member 2 is energized 75 by being connected to the contact member 1 through the medium of the collector W, the coil 20 will be energized as it has its terminals connected to the contact member 2 by the conductor 29, and to the ground 80 by the conductor 30.

When the coil 20 is energized the arm 22 will be raised and engage the contacts 23 and 24 and will break its engagement with the contact 25, but, as already stated, the 85 engagement is not broken at contact 25 until the engagement is made at contacts 23 and 24. If this were not the condition, then there would be a vicious arcing at contact 25 as the circuit would be completely broken 90 at this point, but by making the relation of make and break as stated, the contact member 1 will be thrown into electrical engagement with the trolley conductor 3 through the conductor 31 whereby the coil 10 will be 95 duly energized and the contact member 1 will remain energized. If the coil 10 were left in circuit while the collector engages the contact pan P the car operator could inadvertently change the position of the track 100 switch if he should enter the pan with "power off" and before he left it should change his controller to "power on" as in that case the arm 12 would be brought into engagement with the contact 14 and the 105 solenoid 5 would be energized while it was the original intention to energize the solenoid 4.

As soon as the arm 22 is raised and engages the contact 23, current will flow 110 through the conductor 32, coil 21, and conductor 33 to the arm 12 thereby energizing the same. When the coil 21 is energized it becomes a stick or holding coil for the arm 22 and will maintain the arm 22 in engagement with the contacts 23 and 24 as long as current is flowing through the solenoid 4 or 5 regardless of whether the collector is in contact with the pan P or has passed beyond the pan.

Under these circumstances it is necessary 120 to provide means to open the circuit supplying current to the switch arm 12 in order that the system may be returned to normal for the operation by a following car, and also to prevent the current flowing through the solenoid 4 or 5 beyond a predetermined 125 time as these solenoids are usually designed to operate under a high current for a short time and are, therefore, in danger of being 130

injured by a prolonged application of current, as would be the case if the collector W should come to rest upon the pan P.

Therefore, I provide an electrically operated switch D provided with two controller coils 34 and 35. The coil 35 is normally energized due to its terminals being connected to the switch arm 18 by the conductor 26 and to the conductor 28 by the conductor 37 thereby its arm 18 is normally raised and held in engagement with the contact 19. The coil 34 has its terminals connected to the switch arm 18 through the conductor 36 and to the switch arm 12 through the conductor 38, therefore, the coil 34 is energized only when the switch arm 12 is energized through the closing of the switch C.

As soon as the switch arm 22 is closed upon its contacts 23 and 24 and as there is practically no resistance between the trolley conductor 3 and the switch arm 18, the coil 35 will be practically short circuited on account of its terminals being connected to the switch arm 18 and to the conductor 28 leading to the trolley conductor, therefore, the coil 35 will be de-energized. Likewise the coil 34 will be short circuited after it is connected to the switch arm 12 and to the switch arm 18 and no current can flow there-through while the switches C and D are closed, and the arm 12 in engagement with its contact 13. The de-energizing of the coil 35 and non-energizing of the coil 34 upon the closing of the switch C will permit the switch D to open and as soon as this occurs the short circuit is removed from the coils 34 and 35 and they will be energized, but they are wound for equal energizing capacity and connected in differential, therefore, they will maintain the switch D in an open position and will prevent current flowing through the conductor 17 and the solenoid 4. The switch D will not open immediately upon the de-energizing of the coil 35, but due to the residual magnetism therein and the relation of the arm 18 to the magnetic core of the coils 34 and 35, all of which is well known to those skilled in the art, a time lag is provided in the switch D hence the switch D will open after a predetermined time after the closing of the switch C, when the arm 12 engages the contact 13 as is the case when the collector engages the pan with "power off."

In order to open the circuit 15 leading to the solenoid 5 which will be closed when the collector engages the pan P with "power on", I make use of the coil 11 for this purpose. It will be noted that the coil 11 is connected to the conductor 16 by the conductor 39 and is connected to the conductor 15 by the conductor 40, therefore, whenever the conductor 16 is energized, current will flow through the coil 11 and out through the conductor 15 to ground through the sole-

noid 5. The coil 11, however, has its winding so proportioned that it will not be sufficiently energized to raise the arm 12, but if the arm 12 has been raised by the coil 10 the coil 11 will hold the arm in a raised position. It will also be evident that when the conductor 16 is energized it is due to the fact that the collector has engaged the pan P with "power off", therefore, the energizing of the coil 11 when the conductor 16 is energized has no effect upon the arm 12. If, however, the arm 12 has been raised due to the collector engaging the pan P with "power on" then the coil 11 becomes a holding or stick coil and current will then flow through the coil up through the conductor 39 and from the conductor 16 through the solenoid 4 to ground. It will also be evident that as long as the switch D remains closed that the coil 11 will be energized regardless of whether the collector is in engagement with the pan or has passed off the pan.

It will be noted that when the arm 12 engages the contact 14 and is energized that the coils 34 and 35 do not operate under a short circuit, but each coil is immediately energized, but in differential relation as soon as the arm 22 engages the contact 23, and a time lag is also provided by this means against the switch D opening immediately. As soon as the switch D does open, however, the circuit by which the coil 11 is energized will be broken and its holding effect become nil and the arm 12 will return to its normal position in engagement with the contact 13. The switch 18, however, cannot close as long as the arm 22 remains in engagement with the contact 23 and this engagement will take place as long as the collector is in contact with the pan P or for a period of time after the collector has left the pan while the switch D remains closed.

The flow of current in the coil 11 is reversed, depending upon which the system is working, "power on" or "power off" the motors.

If in approaching the track switch the car operator desires to go "straight ahead", he will turn his controller to the "power off" position so as to pass over the pan P with his controller in the "power off" position. As soon as the collector engages the pan the switch C will be operated to close the circuit through the solenoid 4 and the circuit at the contact 25 will be opened as in Fig. 3. The switch D will open after a predetermined time (see Fig. 4) after the collector has engaged the pan P and while still in engagement, providing the car is moving sufficiently slow, but if the car is moving fast and the collector passes the pan P before the switch D opens, the switch 22 will be maintained closed on account of the holding coil 21 being energized until the switch D opens. If the car should come to

rest for any reason with the collector in contact with the pan P and should later start up, the throwing of the controller to "power on" will not energize the coil 10 for the reason that its circuit is open at the contact 25 and the contact member 1 is deriving its current from the trolley conductor through the conductor 31 after the switch C is closed due to the energizing of the coil 20 as long as the collector engages the pan. From this it will be seen that the solenoids 4 and 5 are supplied with current for a predetermined time regardless of the position of the current collector after it has set the system in operation with "power off".

If the car operator desires to take the "curve" when he approaches the pan P, he will throw his controller to the "power on" position. In this case the coil 10 will be energized and the switch C operated and the arm 12 raised into engagement with the contact 14 as shown in Fig. 5. The opening of the circuit through the coil 10 at 25 is under a short circuit due to the arm 22 engaging the contact 24 prior to the opening of the circuit at the contact 25, therefore, the arcing is either eliminated or reduced to a very small amount. The holding coil 11 comes into operation immediately, however, and maintains the arm 12 in engagement with the contact 14 until the switch D opens after a predetermined time which may be while the collector is still in engagement with the pan or after it has passed beyond the pan. It will be noted that should the car for some very remote reason stop with its controller in engagement with the pan P after it has engaged it with "power on" and the switch D has opened, that the switch 12 will then drop back into engagement with the contact 13, but this cannot operate the track switch to the "straight ahead" position for the reason that the circuit through the solenoid 4 is open at the contact 19 and held open as long as the collector engages the pan P due to the energizing of the coil 20.

The modification shown in Fig. 6 is substantially the same as the system shown in the other figures with the exception that across the terminals of the coil 10 I place a resistance R which is normally in shunt with the coil 10, but when the switch C has been energized the conductor 27 is opened at the contact 25 and, therefore, the resistance R is no longer a shunt across the coil 10, but does remain as a connection between the contact member 1 and the trolley conductor 3.

The object of the resistance R is to decrease the current which will flow through the coil 10 and, therefore, decrease the current which must be broken by the switch C at the contact 25. The use of the resistance R permits the system being used without the conductor 31 as the resistance R will

form a connection between the pan and the trolley conductor both when the switch C is opened and closed. The winding of the coil 10 is so proportioned that it will operate to pick up the arm 12 when the current due to the collector engaging the pan with "power on" is the same as will cause the coil 10 to pick up the arm 12 in the previously described figures. It will be evident that the energizing of the coil 10 depends upon the drop of potential across the resistance R and, working on this principle, the current in the coil 10 will be quite small as compared with the current which flows through the coil 10 in the system shown in the other figures, therefore, the current which will be broken in the contact 25 will be much easier to control than in the first system.

It will be evident to those skilled in the art that many changes are possible from the particular system herein described, but which will fall within the scope of my invention.

I claim:

1. A switch operating system comprising in combination, an electrically operated track switch, a branched operating circuit, an electrically operated switch to position said branch circuits, means to position said electrically operated switch comprising a coil and an operating circuit therefor, and means to open said operating circuit after said coil has operated to operate said electrically operated switch.

2. A switch operating system comprising in combination, an electrically operated track switch, a branched operating circuit whose branches connect to the track switch operating mechanism, a controlling switch therefor having an operating coil to position the controlling switch relative to the branch circuits and an operating circuit therefor and means to open the last said operating circuit by a moving car.

3. A switch operating system comprising in combination, an electrically operated track switch, a contact pan, operating circuits to said track switch, a controlling switch therefor, provided with a coil and operating circuit therefor connected to a source of electrical supply and to the pan, an electrically operated switch to open the circuit to the coil and close a circuit from the source of power to the pan.

4. A switch operating system comprising in combination, an electrically operated track switch, a contact pan, operating circuits to said track switch, a controlling switch therefor, provided with a coil and operating circuit therefor connected to a source of electrical supply and to the pan, an electrically operated switch to open the circuit to the coil and close a circuit from the source of power to the pan and close the circuits to said track switch.

5. The combination with a trolley conductor, a contact pan, an electrically operated track switch and electrically operated means to control the directional operation of the 5 track switch, of electrically operated means to close a normally open circuit leading to the track switch, open a normally closed circuit to the first said means and close a normally open circuit from the conductor to 10 the pan.

6. A switch operating system comprising in combination, an electrically operated track switch, a contact pan, operating circuits to said track switch, a controlling 15 switch therefor, provided with a coil and operating circuit therefor connected to a source of electrical supply and to the pan, an electrically operated switch to open the circuit to the coil.

20 7. A switch operating system comprising in combination, a trolley conductor, a contact pan to be engaged by a current collector, an electrically operated track switch, a switch to control the directional operation of the 25 track switch and having an operating coil and a normally closed circuit connected to the conductor and the pan, an electrically

operated switch normally closing the said circuit and operating to open said circuit when the collector engages the pan. 30

8. A switch operating system comprising in combination, a trolley conductor, a contact pan to be engaged by a current collector, an electrically operated track switch, a switch to control the directional operation 35 of the track switch and having an operating coil and a normally closed circuit connected to the conductor and the pan, an electrically operated switch normally closing the said circuit and operating to open said circuit 40 when the collector engages the pan and simultaneously close a circuit from the conductor to the pan.

9. A switch operating system comprising an electrically operated track switch, a 45 branched operating circuit therefor, a controlling switch for said branched circuit and having an operating coil and connections to said coil, means to open the circuit to said coil and automatically controlled 50 means to open the branches of said branch circuit after a predetermined time.

In testimony whereof I affix my signature.
GEORGE A. MEAD.
